(57) **CLAIM**

The ornamental design for a display screen with a machine learning confidence score graphical user interface as shown and described.

DESCRIPTION

FIG. 1 is a front view of a first embodiment of a display screen with a machine learning confidence score graphical user interface; and,

FIG. 2 is a front view of a second embodiment of the display screen with a machine learning confidence score graphical user interface.

The present invention relates to a display screen with a machine learning confidence score graphical user interface. The display screen or user interface could be that of a computer server, a laptop computer, a mobile phone, a telephone, a tablet, a smart swatch, or other electronic device. The outermost broken-line rectangle illustrates a display screen and forms no part of the claimed design. The remaining broken lines illustrate portions of a user interface and form no part of the claimed design.
